HARRY J. WALKER, OF CHICAGO, ILLINOIS.

DISPENSING APPARATUS.

1,250,535.

Specification of Letters Patent.

Patented Dec. 18, 1917.

Application filed September 15, 1911, Serial No. 649,470. Renewed March 3, 1917. Serial No. 152,437.

To all whom it may concern:

Be it known that I, HARRY J. WALKER, of Chicago, in the county of Cook and State of Illinois, have invented certain new and useful Improvements in Dispensing Apparatus, of which the following is a specification.

My present invention relates in general to dispensing apparatus, and more particularly to apparatus for dispensing fluids, and has special reference to the provision of an improved form of pump device which is particularly useful in dispensing beverages and especially beverages containing a portion of flavoring syrup.

The principal objects of my present invention are the provision of an improved form of dispensing pump device; improved mechanism for operating the dispensing pump; improved mountings for the pump and its ejector nozzle, and for the pump operating device, respectively, and improved relative arrangement of such several parts and the syrup container, whereby a much more compact form of so-called "soda fountain" than is now available may be built, and whereby not only may much waste space be utilized, but also the capacity of any given fountain largely increased, together with such other objects as may hereinafter appear.

In attaining the foregoing objects I have provided a construction, one embodiment of which is illustrated in the accompanying drawing, wherein—

Figure 1 is a sectional elevational view taken on the line I—I of Fig. 2, illustrative of a dispensing apparatus embodying my improvements in a preferred form;

Fig. 2 is a plan view, partly in section, taken on the line II—II of Fig. 1; and

Fig. 3 is an elevational view of a portion of a soda fountain, embodying several of the elements illustrated in Figs. 1 and 2, in the direction indicated by the arrow in Fig. 1.

Referring now more particularly to Fig. 1, it will be observed that I have here illustrated a conventional type of counter wherein there is employed a longitudinal supporting member 10 and a top 11.

In carrying out my invention I preferably employ in combination therewith a secondary wall 12, forming an insulating space 13, an insulating wall 14, preferably formed of cork, for the ice chamber indicated at 15,

the remaining walls of the chamber not being shown, but normally extending to the right of and below the broken line 16.

In order to provide the chamber for the reception of the syrup containers, 17, I make use of a partition 18 having an upwardly turned portion 19, such partition being supported above the lining 14 and against the wall 12, the chamber 20 thus formed, as well as the chamber 15, being preferably lined with sheet zinc, or other suitable material as indicated at 21—22, both to facilitate cleansing and to aid in maintaining the relatively low temperature desired. Since the containers 17, with their respective pump and pump-actuating devices are substantially duplicates, I will now proceed to the description of one complete embodiment of the dispensing device proper.

As will be apparent on inspection of Fig. 1, the container 17 is provided at its bottom with a welt 23 for receiving the pump cylinder 24, conveniently rounded and adapted to receive a piston 25, operable by a piston rod 26, the cylinder being preferably provided at its bottom with a port 27 whereby communication is established with the discharge pipe 28 which terminates in the ejector nozzle 29.

To the end that the piston 25 may be normally supported above the upper margin 30 of the cylinder 24, in order that the fluid contents of the container 17 may have ready inlet to the cylinder 24, and yet such piston be prevented from movement into inoperative relation to such cylinder, the cylinder is provided with a plurality of upstanding guides 31—31, and the piston rod 26 is provided with a detachable extension 32 passing through the cover plate 33 and terminating in a housing 34 between which and the cover plate 33 a spring 35 is inserted. In order to maintain the proper relation between the piston rod 26 and discharge pipe 28, and the cover plate 33, to the end that the cylinder 24 may be quickly adjusted in position, the nozzle 29 is attached to the pipe 28 above such plate 33 and a lock nut 36 is utilized on the opposite side of such plate. For closing the chamber 37 containing the operating mechanism now to be described, and thereby preventing entrance of foreign material to either the receptacle 17 or to the moving

parts, I make use of a face plate 38 which is held in position against a shoulder 39 on the said nozzle 29 by means of a lock nut 40.

Referring now more particularly to Figs. 5 2 and 3 it will be observed that for the purpose of actuating the pump mechanism I preferably employ a double lever device pivoted at 41 to the wall 12, one arm 42 being provided with an extension 43 acting upon a shoe 44 formed upon the housing 34 and the other arm 45 having pivotal engagement, as indicated at 46, with a push rod 47, preferably supported by the angle bar 50. Thus when such push rod 47 is moved from its position indicated in the 15 full lines, (Fig. 1), to its position indicated by the dotted lines, the piston 25 will be depressed to the bottom of the cylinder 24 and the contents driven through the discharge pipe 28 into a glass or other receptacle, such as is indicated at 48.

In order that the extent of movement of the piston 25 into the cylinder 24 may be varied as circumstances require, I preferably provide the housing 34 with a sleeve 49 having threaded engagement therewith and movable vertically relatively thereto.

From the foregoing specification it will be evident that upon removal of the cover plate 51, (Fig. 3), any one of the receptacles 30 17 may be tipped forward against the partition member 19, accompanied by the pump and ejector members and the face and cover plates pertaining to such receptacle. These 35 as a unitary structure, may be lifted out of the receptacle, which may be refilled, or a new receptacle substituted and replaced, all without demounting or unnecessary disturbance of the actuating mechanism.

40 It will be further observed, firstly, that by virtue of the construction and arrangement described the implacement of the several containers, with their respective pump actuating mechanisms, below the counter top 45 11 and substantially within the margin thereof, is readily effected, and that thereby much space heretofore wasted is saved, more space available for working room is gained; and secondly, that improved facilities for 50 cooling the contents of the receptacles are attained and a construction which is readily kept in a clean and sanitary condition is provided, and finally that a shelf upon which glasses may be placed for the reception of 55 the ejected syrup is arranged, without sacrifice of space or incurring of additional expense therefor.

Other advantages of the construction will be obvious to those who are skilled in the 60 art to which my invention pertains.

Having thus described my invention and illustrated its use, what I claim as new and desire to secure by Letters Patent is:

1. A dispensing apparatus comprising in 65 combination a fluid container, a support

therefor, a stationary pump cylinder and manually operated means for imparting movement to the piston of the pump supported by said support and carried independently of the pump whereby the pump may be removed without removal of said 70 actuating means.

2. A dispensing apparatus comprising in combination a fluid container, a stationary pump cylinder, and independent means for 75 actuating the piston of the pump adapted for contact with but disconnected from the pump whereby the pump may be removed without removal of said actuating means.

3. A dispensing apparatus comprising in 80 combination a fluid container, a stationary pump cylinder, a support and means adapted to contact with but disconnected from and independent of the pump for actuating the piston of the pump carried by said support, whereby the pump may be removed 85 without removal of said actuating means.

4. A dispensing apparatus comprising in combination with a counter-top having a support therefor, a fluid container, a pump and thrust operated means for actuating the pump, said fluid container and pump and a support for the pump actuating means being mounted within the margin of said counter-top, the pump being provided with 90 discharge means located below said counter-top.

5. A dispensing apparatus in combination with a counter-top having a support therefor, a fluid container and a pump, thrust 100 actuated means carried independent of the pump for imparting movement to the pump and mounted within the outer margin of said counter-top, whereby the pump may be removed without removal of said actuating 105 means.

6. A dispensing apparatus comprising in combination with a counter-top having a support therefor, a fluid container and a pump, thrust 110 operated means for imparting movement to the pump supported within the margin of the counter-top and independently of the pump whereby the pump may be removed without removal of said actuating means.

7. In a dispensing apparatus in combination with a counter-top having a support therefor, a fluid container and pump, means for operating the pump comprising a bell crank lever pivotally mounted on said support and adapted to contact with but disconnected from the pump, whereby the pump may be removed without removal of said lever, and thrust operated means for actuating said lever.

8. In a dispensing apparatus, in combination with a counter-top having a support therefor, a fluid container and a cover therefor, a force pump device comprising a stationary cylinder, a piston rod having at one 125

- end a piston and at the other end an extension passing through said cover and provided with a housing, resilient means for lifting said rod interposed between said housing and cover, a discharge pipe leading through said cover and terminating in an ejector and a lever for actuating said piston rod supported adjacent said counter-top and independently of the pump device whereby the pump device may be removed without removal of the actuating means.
9. In a dispensing apparatus, in combination with a counter-top having a support therefor, a fluid container and a pump and means for operating the pump supported independently of the pump comprising a bell crank lever pivotally mounted on said support, and engaging the pump and a push rod for actuating said bell crank.
10. A dispensing apparatus comprising, in combination with a counter-top having a top, a fluid container, a pump, and thrust operated means for actuating the pump, all mounted below said counter-top and said fluid container, the pump and a support for the pump actuating means being within the outer margin therefor, the pump being provided with means for discharging the fluid laterally.
11. In a dispensing apparatus, in combination with a counter top having a support therefor, a fluid container, and a pump, means for operating the pump comprising a bell crank lever pivotally mounted on said support and engaging the pump, and a push rod for actuating said lever.
12. In a dispensing apparatus, in combination with a counter top having a support therefor, a fluid container, and a pump, means for operating the pump comprising a bell crank lever pivotally mounted on said support and engaging the pump, a push rod for actuating said lever, and a support for said push rod carried by said counter top.
13. In a dispensing apparatus, in combination with a counter top having a sup-

port therefor, a fluid container, and a cover therefor, a force pump device comprising a pump cylinder, a piston rod having at one end a piston and at the other end an extension passing through said cover and provided with a housing, resilient means for lifting said rod interposed between said housing and cover, a discharge pipe passing through said cover and terminating in an ejector, a face plate apertured for the passage of said ejector and supported thereby, and a lever for actuating said piston rod supported adjacent said counter top and independently of the pump device, whereby said pump device may be removed without removal of said actuating means.

14. A dispensing apparatus comprising, in combination, a chamber having therein a plurality of fluid containers each provided with a pump and laterally removable from said chamber, independent means for actuating each of said pumps, independent face plates for closing a part of one face of said chamber located below the top of said chamber, and a cover common to a plurality of containers for closing another part of said face.

15. A dispensing apparatus comprising, in combination, a chamber having therein a plurality of fluid containers each provided with a pump and laterally disposed pump discharging means, independent means for manually operating each of said pumps, independent face plates for closing a part of one face of said chamber substantially vertically arranged and each being carried on one of said pump discharging means, and a cover common to a plurality of containers for closing another part of said face.

In testimony whereof I have hereunto signed my name in the presence of the two subscribed witnesses.
